UNITED STATES PATENT OFFICE

JACOB G. PECK, OF PORTLAND, OREGON

OIL AND GAS SEPARATOR

Application filed March 2, 1927. Serial No. 172,164.

My invention relates to compressors employed in mechanical refrigeration and has for its primary object the separating of the lubricant used in the compressor from the refrigerant as well as providing automatic means for the return of the same to the crank case of the refrigerating machine.

A further object of my invention consists in effecting the separation immediately after the compression of the refrigerant materials and therefore effecting the separation when the compressed refrigerant is at its highest temperature.

A still further object of my device consists in so constructing my device that the same may be made to serve as a separator and as a head for the refrigerating machine.

I have observed in my work as a refrigerating engineer, that the principal trouble encountered with refrigerating systems consists in the admission of the lubricating material into the refrigerant material and carrying the same into the expansion coil and into the expansion chambers for the refrigerant material and that the refrigerant becomes so thoroughly and completely impregnated with the lubricant that it loses its efficiency as a refrigerating medium and that when the saturation becomes sufficiently complete it ceases to perform its function almost entirely as a refrigerating medium. I have observed, and I am aware, that many attempts have been made to effect this separation, but I am not aware that any attempt has been made to effect this separation within the head of the refrigerating machine.

I have observed that this result can be had most effectively while the refrigerant gases are in the highly heated state and therefore I have made my device to conform to the head of the compressor unit and effect the separation at that point.

The refrigerant materials and the lubricant, in most cases have different specific gravities, and in my new and improved device I effect the separation because of this difference in the specific gravities, and cause a precipitation of the heavier of these elements and cause the same to be deposited in a sump within the main frame of the device.

Automatic means are provided within the sump for the delivery of the trapped materials therefrom into the crank case of the refrigerating machine, the automatic device consisting primarily of a valve and an actuator therefor adapted to maintain the level of the precipitated materials within predetermined limits of the level heights.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a front elevation of a refrigerating machine with one of my new and improved traps associated as the head of the compressor.

Fig. 2 is a side elevation of the mechanism illustrated in Fig. 1.

Fig. 3 is a longitudinal cross section view, in side elevation, of my new and improved device, shown removed from the compressor.

Fig. 4 is a longitudinal, cross sectional view, taken on line 4—4 of Fig. 3, looking in the direction indicated.

Fig. 5 is a cross section view, taken on line 5—5 of Fig. 3, looking in the direction indicated.

Fig. 6 is a fragmentary, side elevation, of the actuator of the valve and illustrates its connections with an automatic release valve from the sump.

Like reference characters refer to like parts throughout the several views.

1 is the crank case base of a compressor for a refrigerating machine and 2 is the cylinder thereof, having a flange 3, terminating the same. In my new and improved device, 4 is a cylindrical casing, having flanges 5, disposed upon the lower side thereof and connected to the flange of the cylinder of the refrigerating machine through suitable fastening elements 6, my device thus forming a head for the compressor. The inlet 7, leading into my device has disposed

therein a valve 8, having a valve stem 9, for actuating the same therewith, the object of which is to facilitate the exhausting of the coilage and refrigerant chambers before the starting of the device. The passage 7, leads 5 into the annular passage way 10 of my device. A diaphragm 12, being positioned within the chamber to prevent the direct passage of the refrigerant therefrom, and to form compartments within the casing. Dis- 10 posed within the chamber 11, is a bell shaped element 13, having outwardly sloping side walls from the central body or member 14, which has a series of indentures 15, in stepped relationship, disposed upon the under side thereof, the general contour of 15 which is upwardly inclined into the entrance 16, to the interior space 16A of the member 14. A series of outlets 17, are disposed in the upper end of the central section 14, through 20 which the compressed refrigerant material is permitted to pass into the chamber 18, associated therearound. The refrigerant material then passes through the outlet 19, through the coilage for the expansion 25 of the same. A series of baffles 20, are disposed within the central chamber 16A, the object of which is to provide a circuituous passageway within the chamber 16A which 30 aids in precipitating the lubricant into the sump chamber, as the refrigerant passes upward therethrough. The device is secured to the head 21, and may be adjusted by means of an opening 22, disposed in the 35 neck thereof into which an adjusting wrench may be placed, the opening being closed by a threaded member 23.

I have found by constructing a separator, as herein described, that the lubricant material, which is of a different specific gravity than that of the refrigerant material, 40 will separate and the lubricant will be precipitated within the chamber 24. Disposed within the chamber 24, is a float 25. The 45 float 25 is in hinged relationship with its supporting element about the supporting pin 26. A spring 27 normally maintains the ball or float 25 in repressed position and contacts with the end of the lever or arm 50 30 which is rounded. Disposed within the block 28, to which the ball 25 by means of its supporting lever or arm is hinged about 26, is a valve seat 29, and secured to the lever 55 30 of the ball, is a valve 31, which is raised into and out of engagement with the valve seat 29, as the ball is raised and lowered through the action of the lubricant trapped within the sump or compartment 24. Great care should be taken in assembling the ball 60 30 within the sump chamber to prevent the lifting of the valve 31 from its seat 29, until the lubricant level within the chamber is substantially above that of the valve seat 29, and care should be exercised to prevent 65 the valve closing before the lubrication level

has been lowered beyond that of the valve seat 29, thus furnishing a valve that is at all times seated by the lubricant trapped therein. An outlet 32, leads the trapped lubricant into the conductor 33 that conducts the same from the trap into the crank case 1, of the refrigerating machine. 70

While the form of mechanism herein shown and described is admirably adapted to fulfill the objects primarily stated, it is 75 to be understood that it is not intended to confine the invention to the one form of embodiment herein shown and described, as it is susceptible of embodiment in various forms, all coming within the scope of the 80 claims which follow. 85

What I claim is:—

1. In an oil and gas separator, a casing, a diaphragm dividing the interior of said casing into an upper and a lower compartment, a bell shaped member penetrating said diaphragm and affording communication between the two compartments, the lower portion of said bell-shaped member flaring outwardly and downwardly thereby defining an annular passageway communicating with the lower compartment, an inlet passageway communicating with the aforesaid annular passageway and an outlet passageway leading from the upper compartment. 90

2. In a device as claimed in claim 1 wherein in the under side of the aforesaid bell-shaped member is characterized by spaced annular indentures to provide a surface for the collection of oil film and droplets. 100

3. In an oil and gas separator, a casing, a diaphragm dividing the interior of said casing into an upper and a lower compartment, a bell-shaped member penetrating said diaphragm, said bell-shaped member having a passageway therethrough affording communication between the aforesaid compartments, the lower portion of said bell-shaped member flaring outwardly and downwardly thereby defining an annular passageway communicating with the lower compartment, an inlet passageway communicating with the aforesaid annular passageway, an outlet passageway leading from the upper compartment, and a plurality of horizontally disposed plates so arranged within the bell-shaped member that the passageway therethrough follows a circuitous route. 110

4. In a device of the class described, the combination of a casing provided with an inlet passageway, a diaphragm disposed within and dividing the casing into compartments, one of which communicates with the aforesaid passageway, an element suspended from the diaphragm terminating at its lower portion in a bell shaped outwardly sloping annular surface, on the underside of which are disposed a series of indentures in stepped relation with each other, a chamber disposed central of the diaphragm and extend- 115 120 125 130

ing upwardly there through, a series of baffles disposed in said chamber, and there being an outlet port extending from the casing above said diaphragm.

5. In a device of the class described, the combination of a casing provided with an interior chamber, there being a passageway leading into said chamber, a diaphragm within said casing dividing said chamber into two compartments, a central member carried by said diaphragm, there being a passageway through the central member affording communication between the two compartments, the lower portion of said 10 member constituting an outwardly sloping annular wall, having its under surface composed of indentures in stepped relation from its outer edge to the last mentioned passageway, and a series of baffles projecting into 15 the last mentioned passageway.
